(57) **CLAIM**

The ornamental design for an extruded housing for light emitting diode lighting system, as shown and described.

DESCRIPTION

FIG. 1 is a perspective view of my new ornamental design for an extruded housing for light emitting diode lighting system, shown with end caps for illustrative purposes;

FIG. 2 is a perspective view of the extruded housing for light emitting diode lighting system depicted in FIG. 1;

FIG. 3 is a top plan view of the extruded housing for light emitting diode lighting system depicted in FIG. 2;

FIG. 4 is an end elevational view of the extruded housing for light emitting diode lighting system depicted in FIG. 2;

FIG. 5 is a bottom plan view of the extruded housing for light emitting diode lighting system depicted in FIG. 2;

FIG. 6 is a side elevational view of the extruded housing for light emitting diode lighting system depicted in FIG. 2; and,

FIG. 7 is a perspective view of the extruded housing for light emitting diode lighting system depicted in FIG. 1, shown mounted to a food guard system for illustrative purposes.

The broken lines in the drawings of the extruded housing for light emitting diode lighting system are for illustrative purposes only and form no part of the claimed design.
